UNITED STATES PATENT OFFICE

2,534,100

CONTAINER FOR COSMETICS

John G. Baumgartner, Oswego, Ill., assignor to
Maybelline Company, Chicago, Ill., a corpora-
tion of Illinois

Application April 16, 1947, Serial No. 740,617

1 Claim. (Cl. 220—41)

1

The present invention relates to a new and improved cosmetic container and a method of assembly thereof and more particularly to a container which is capable of being manufactured on a mass production basis at a minimum cost.

Various cosmetic preparations are extensively sold on the market in rather decorative containers often formed of a suitable material such as plastic or the like. For example, it has been common practice to sell mascara in a suitable container which may be carried in a lady's handbag or purse. Such cosmetic containers normally comprise a partitioned container for holding a cake of mascara or other suitable preparation for coloring the eyelashes, together with an applicator therefor in the form of a brush or the like. A cover generally of hinged construction is normally provided for the box or container. The cover and box portions of such a container could be constructed with a minimum of expense out of a suitable plastic or the like but the assembly process of hingedly relating the cover and box has been a major item of expense. At the same time it is desirable that such a container for a cosmetic preparation when bounced around in a handbag or pocketbook will not spill its contents into the pocketbook so as to come in contact with the other items within the bag which might be colored, stained or otherwise harmed by contact therewith. Accordingly, it would be desirable to provide a container of the type referred to above which is very inexpensive from a manufacturing standpoint as well as an assembly standpoint and which is substantially incapable of spilling its contents so as to cause the undesirable results referred to above.

Accordingly, it is an object of the present invention to provide a new and improved container including a cover therefor.

It is another object to provide a new and improved method of assembling and releasably interlocking a cover and container for a cosmetic preparation.

Further objects and advantages of the present invention will become apparent as the following description proceeds and the features of novelty which characterize this invention will be pointed out with particularity in the claim annexed to and forming a part of this specification.

For a better understanding of the present invention reference may be had to the accompanying drawing in which:

Fig. 1 is a perspective view of a container including a box and cover embodying the present invention with the parts shown in disassembled relationship;

Fig. 2 is a top view of the container shown in closed position; and

Fig. 3 is an enlarged sectional view showing the interlocking means for preventing dis-

2

assembly of the cover from the box once these parts have been assembled.

Referring now to the drawing, there is illustrated a container generally designated at 10 comprising a box 11 and a cover 12. Preferably, the box 11 and the cover 12 are formed from a suitable plastic material which can be made in any color and which provides a very pleasing appearance. As illustrated, the box 11 is of rectangular configuration having a bottom portion and four sides 11a, 11b, 11c and 11d arranged perpendicularly to said bottom portion. A suitable partition 13 may be provided so as to divide the box into two compartments, the partition 13 extending longitudinally of the box 11. As illustrated in Fig. 1, one of these compartments is adapted to contain a suitable brush 14 by means of which the mascara or other cosmetic preparation may be applied. The other compartment is adapted to contain a suitable preparation such as mascara illustrated at 15 in Fig. 1 of the drawing in the form of a cake of a size so as to just fit into said other compartment.

The cover 12 is constructed in the manner of a match box cover and is adapted to be arranged in telescopic relationship with the box 11 in a manner which will be well understood by those skilled in the art. In other words, the cover 12 substantially defines a closed container having at least one open end 12a into which the box 11 may be inserted. When the container is closed the box 11 and cover 12 are in the completely telescoped position indicated in Fig. 2 of the drawing.

For the purpose of preventing disassembly of the box 11 from the cover 12 once they have been assembled, there are preferably provided at the junction points between the end wall 11d of the box 11 and the walls 11a and 11b projections or ear portions 18 which are integrally formed with the box 11. These projections 18 preferably have rounded surfaces 18a which in effect are extensions of the outside surface of the wall 11d. On the side opposite the rounded surface 18a each of the projections is provided with a shoulder portion 18b. Similarly the cover 12 is provided with cooperating projections or ears 19 defined at one end thereof extending into the open end 12a which actually is the entrance to the cover 12. These projections are preferably of the same form as the projections 18 having a rounded portion 19a facing toward the outside of the cover and a shoulder portion 19b facing in the opposite direction. The projections 18 and 19 are so constructed so as to tend to prevent the box 11 from being inserted into the cover 12 through the entrance 12a. However, in accordance with the present invention, the projections 18 and 19 are so constructed that upon the application of sufficient force to tend to cause the box and

cover to telescope together the parts of the box and cover are distorted or deformed sufficiently so these cooperating projections 18 and 19 can slip past each other whereupon subsequent disassembly of the cover 12 from the box 11 is prevented by the engagement of the shoulders 18b of the projections 18 with the shoulders 19b of the projections 19, as is clearly shown in Fig. 3 of the drawing. It will be apparent that the rounded portions of the projections 18 and 19 aid in the assembly operation by providing a sort of wedge effect to cause the necessary distortion so that the projections may slip past each other. However, the cooperating shoulder portions 18b and 19b as will be apparent from Fig. 3 clearly prevent any subsequent disassembly of the members 11 and 12.

To facilitate opening the container comprising the box 11 and the cover 12, the end wall 11c of the box 11 is preferably provided with extensions 20 which may readily be grasped by the fingers to manipulate the container from the closed to the open position. Also in accordance with the present invention, the projections 18 are preferably arranged to produce a slight frictional engagement with the walls of the cover 12 so that the container will remain in the closed position unless an opening force is applied on the extensions 20 of the box 11. It will be understood that this frictional force is very small so as merely to prevent inadvertent opening of the box while bounced around within the handbag, pocketbook or other means in which it is carried. If desired, this slight frictional force could be provided by various other means such as the frictional engagement of the partition 13 with the cover 12 or any other suitable arrangement.

In view of the detailed description included above, the construction and method of assembly of the container of the present invention will be obvious. It will be understood that the box 11 and cover 12 with the integral projections or extensions can be manufactured at a minimum of cost. Furthermore, the assembly of the box and cover can be accomplished in a very small period of time merely by forcibly inserting the box 11 into the cover 12 so that the projections 18 move past the projections 19 whereupon subsequent disassembly is prevented. It will be apparent that this method of assembly is considerably less expensive than hingedly relating a cover to a box as was heretofore customary. In addition, by providing the slight frictional drag, the box and cover will remain in the closed position once they are closed whereby the contents thereof cannot be strewn around within the handbag or pocketbook so as to come in contact with other objects contained therein. Although the present invention has been described particularly in connection with a container for mascara, it should be understood that it can also be used for containing other cosmetic preparations in which case a suitable mirror might be attached to one of the larger exterior surfaces of the cover 12.

While there has been described a particular embodiment of the present invention, it should be understood that various changes and modifications thereof can be made without departing from the present invention. It is aimed in the

appended claim to cover all such changes and modifications as fall within the true spirit and scope of the invention.

What is claimed as new and desired to be secured by Letters Patent of the United States is:

5 A two-member disposable plastic container for mascara applying materials comprising a rectangular open box member for carrying mascara applying material therein in a readily accessible
10 position, said box member having a bottom, a pair of opposing sides integral with said bottom, and a pair of opposing end walls integral with said bottom and said sides and closing the same, with said box member having an outwardly extending lateral flange projection on each of the sides thereof adjacent one end and comprising together a first set of such projections, and said container also comprising a one-piece rectangular cover member for telescopically receiving said
20 box member, said cover member being open at each end thereof and having a top, a bottom, and two opposing integral closing sides, with the inside cross-sectional dimensions of the cover member being substantially uniform throughout,
25 and with the height of one end wall of the box member being substantially the same as the inside height dimension of the cover member, and an inwardly protruding flange projection on each side thereof at the same end and comprising
30 together a second set of projections, at least one of said two sets of projections having a beveled surface at the edge of each projection initially engaged when the two members are telescoped together so that one set may be pressed past the other set upon the two members being telescoped together, and both of said sets of projections being further shaped to present face abutting surfaces for preventing the complete withdrawal
35 of said box member from said cover member, with
40 said cover member having said box member extending therefrom but not completely separable in one direction and serving as a handle for carrying the container when the box member is open for access thereto, and the end wall at the
45 other end of the box member extending beyond the side edges of the box member to abut the ends of the walls of the cover member to prevent the box member from being telescoped through the cover member in the other direction
50 and separated therefrom.

JOHN G. BAUMGARTNER.
